US0D1039804S

(12) **United States Design Patent** (10) Patent No.: **US D1,039,804 S**
(45) Date of Patent: ** Aug. 27, 2024

(54) **FOOTWEAR MIDSOLE**
(71) Applicant: **adidas AG**, Herzogenaurach (DE)
(72) Inventors: **Stephen P. Dobson**, Nuremberg (DE);
Moritz Hoellmueller, Fuerth (DE)
(73) Assignee: **adidas AG**, Herzogenaurach (DE)
(**) Term: **15 Years**
(21) Appl. No.: **29/813,937**
(22) Filed: **Nov. 2, 2021**

(57) **CLAIM**

The ornamental design for a footwear midsole, as shown and described.

DESCRIPTION

The sole FIGURE is a side view of a footwear midsole showing our new design. The dash-dot-dash lines define the boundaries of the claimed design, and the dash-dot-dash lines and portions of the footwear midsole outside these unclaimed boundaries form no part of the claimed design.
